UNITED STATES PATENT OFFICE.

SPENCER OTIS, OF CHICAGO, ILLINOIS.

DUMP-CAR.

No. 851,372.

Specification of Letters Patent.

Patented April 23, 1907.

Application filed August 13, 1904. Serial No. 220,673.

To all whom it may concern:

Be it known that I, SPENCER OTIS, a citizen of the United States, residing at Chicago, in the county of Cook and State of Illinois, 5 am the inventor of certain new and useful Improvements in Dump-Cars, of which the following is a specification.

My invention relates to that class of dump cars having swinging dumping doors which 10 form a substantial portion of the bottom of the car, means for pivotally supporting such doors, transverse beams mounted upon longitudinal sills and provided with mechanism connected with such transverse beams and 15 dumping doors for raising the doors to closed position, supporting them in such position and permitting them to be opened, and means for operating such mechanism and thereby the doors.

20 The principal object of the invention is to provide a simple, economical and efficient mechanism for supporting and operating the dumping doors of dump cars.

25 A further object of the invention is to provide shaft mechanism operatively connected with the dumping doors for raising them, and permitting them to be lowered, and adapted to form a support for the pivoted sides of the doors.

30 A further object of the invention is to provide means, which is here shown as operated by such shaft mechanism, adapted to be connected with the ends of the swinging doors and mounted between such doors upon 35 the transverse beams for raising the doors to closed position, supporting them in any inclined position and permitting them to be opened by the weight of the load or otherwise.

40 A further object of the invention is to provide suitable supporting mechanism and means for transferring the weight of the doors and any load which may be placed thereon from the mechanisms which operate 45 the doors to such supporting mechanism, and to provide means for releasing the doors from such supporting mechanism.

Other and further objects of the invention will appear from an examination of the drawings and the following description and 50 claims.

The invention consists in the features, combinations and details of construction hereinafter described and claimed.

55 In the accompanying drawings—Figure 1 is an end elevation of a dump car provided

with my improvements, showing the mechanism for operating the main shafts which pivotally support the doors, and also serve in the capacity of operating shafts to raise 60 and lower the doors and hold them in the desired inclined or horizontal positions; Fig. 2 an enlarged transverse sectional elevation, taken on line 2 of Fig. 5, showing the door operating mechanisms with the doors 65 in closed position and illustrating the manner of connecting the operating shaft mechanism and crank-wheels with the doors and hollow transverse beams; Fig. 3 a similar view showing the outside of one of the transverse beams and the arrangement of the depending bracket of the dumping door on the outside, and the sheave pulley with its connections on the inside of such hollow transverse beam; Fig. 4 a transverse sectional elevation in detail of a portion of the 70 car showing a dumping door in inclined open position; Fig. 5 a longitudinal sectional elevation of a portion of a car showing the dumping doors and a sectional end view of 80 the hollow transverse beams as well as the arrangement of the door operating mechanism in connection with such hollow beams; Fig. 6 a detail perspective view showing 85 one of the crank-wheels in dotted lines and the manner of connecting the depending dumping door brackets and thereby the doors operatively with the crank-wheels; and Fig. 7 a detail view in elevation showing 90 the mechanism for supporting the weight of the door independently of the means for operating such door.

In constructing a dump car provided with my improvements, I make a framework including an under frame formed of longitudinal center sills *a* and longitudinal center sills *b*, also arranged near the center of the car. The latter would be termed intermediate sills if employed in a car having side sills, but in my preferred construction the outer side 100 sills are dispensed with, so as to provide the desired space for dumping the load. These longitudinal sills, which may be of any ordinary and well-known construction, are mounted in the ordinary manner upon the 105 bolsters or other supporting members of a railway car. The longitudinal sills, together with the hollow transverse beams *c*, constitute the entire underframing of the car. These hollow transverse beams are each formed of 110 the side members *d* and an upper horizontal member *e*. They are open at the bottom,

the side members being in the form of angle irons having depending portions which form the sides of the beam, and which are much wider than the horizontal portions. A space 5 is thus provided in the open bottom beam between the side members thereof for receiving the door operating mechanisms, as hereinafter described. The side members of each of the transverse beams have horizontally projecting side flange portions *f* by means of which they are connected to the horizontal member *e* of the beam. They thus form, with the longitudinal member, a rigid hollow transverse beam of sufficient 10 strength to support the stress and strains to which it is subjected in use, and adapted to receive on the inside thereof the mechanism for operating the dumping doors. These hollow beams are arranged at intervals upon 15 the upper side of the longitudinal beams and are provided with a central floor portion *g* laid thereon. Dumping doors *h* are arranged intermediate these hollow transverse beams, having suitable cleats *i* in the form of angle 20 irons for strengthening and supporting the doors. These cleats also serve as hinge members, being provided with perforations *j* at one end through which door supporting and main operating shafts *k* extend. These 25 main operating shafts are rotatably mounted in suitable bearings upon the transverse beams through which such shafts extend. If desired, suitable brackets may be mounted upon the longitudinal beams and intermediate 30 the transverse beams for supporting the shafts, though I prefer to mount them directly in the transverse beams, as this arrangement serves to counterbalance the load which is upon the outer ends of the beams. 35 I employ two of these main operating shafts—one for each side of the car. They each pivotally support the entire set of dumping doors upon their respective sides of the car, and it will, of course, be understood the doors 40 may form the entire bottom of the car, or all but the central portion of such bottom, and that the mechanisms here described in connection with the hollow transverse beams are also employed in connection with the end 45 sills or end frames, as shown at the left of Fig. 5, and also that a description of the doors and the mechanisms for operating them on one side of the car applies equally to the same elements on the other side thereof, 50 both being identical.

In order to provide suitable and efficient means for operatively connecting the main operating shafts with the dumping doors for raising and lowering such doors, crank mechanism in the form of a grooved crank-wheel *l*, is mounted upon the inside of each of the 55 hollow transverse beams between the depending side members or flange portions thereof and between the ends of the dumping doors. Each of these crank-wheels is in the

form of two disk portions, which form the main body portion thereof, and between which is mounted a sprocket-wheel *m*, the side portions of the wheel being sufficiently separated to admit between them a suitable sprocket chain *n*—one for each crank-wheel or part of disk-cranks. These chains are mounted upon the sprocket-wheels *m*, or toothed portions of the crank-wheels, and upon similar sprocket-wheels *o* upon the main operating shaft *k*, already described. 70 Each of the crank-wheels is provided with a suitable journal *p*, which is rotatably mounted in perforations or bearings in the side members of the hollow transverse beam, 75 which supports such crank-wheel. 80 Each crank-wheel between the dumping doors is provided on each side and near its outer peripheral edge with a supporting crank-pin *q* extending parallel with the axis 85 of the crank-wheel, and a link *r* is pivotally mounted upon such crank-pin and pivotally connected at its swinging end with a depending bracket *s* mounted upon the adjacent end of the dumping door to be operated and supported thereby. The depending brackets *s* and links *r* are of substantially the same length, and there is one of such brackets upon each end of each dumping door connected with such link by means of a pivot 90 pin *t*, so that the door may thus be raised entirely to its closed position without the link or any portion of the operating mechanism extending above the surface of such door. The crank-wheels at the extreme 100 ends of the car, of course, only require a crank-pin on one side thereof, and while the intermediate crank-wheels are grooved or formed of disks having a space or grooved portion therebetween, and sprocket teeth at 105 the bottom of the grooved portion, the crank-wheels at the extreme ends of the car do not require the central groove, but may have a single disk portion on one side only of the sprocket-wheel portion. 110

It will be readily seen that by the above arrangement the rotation of the crank disks or wheels in one direction, for instance to the right from the position shown in Fig. 2, will permit the dumping door to be lowered by 115 the weight of the load or will lower such door, and the rotation of such crank-wheels in the opposite direction will raise and close the door, so that in its raised position it will form a portion of the bottom of the car. 120 When the parts are in the position shown in Fig. 2 the pivot *q* should be to the left of the axial center of the crank-wheel, so that such crank-wheel may be rotated to the right a sufficient distance to release the supporting 125 mechanism or hooked keeper—hereinafter described—before the weight of the door and its load is transferred from the crank-wheels to such supporting mechanism or hooked keeper. 130

In order to provide suitable means by which the weight of the load may be transferred from the crank-wheels and the other door operating mechanisms, a keeper *u*, in the form of a hook, is pivotally mounted upon each transverse beam on the inner side thereof and adjacent to the crank-wheel upon a pivot *v*. A suitable supporting and guide pin *w* is also mounted upon the transverse beam upon about the same plane with the pivot *v*. It enters a segmental slot *y* in the keeper, so as to permit and guide the movement of such keeper or hook, and together with the pivot pin *v* serves to support the load when transferred from the crank-wheels to such keeper. There is one of these keepers or supporting hooks for each crank-wheel.

In order to enable all of the parts to be so mounted as to be below the plane of the door when in its closed position, each dumping door is provided with a depending stud or arm *2*, having a horizontal portion *3*, adapted to enter the recess formed by the hook portion *4* of the keeper. The keeper and depending stud or arm are of substantially the same length so that when the hook engages the arm the door is in its raised and closed position. All the working parts are thus below the upper surface of the door. The pivotal point of the keeper is to the left of the hook portion thereof so that it acts in the manner of a gravity latch,—in other words, it is thrown by force of gravity into position to support the door and engage the depending stud or arm portion thereof.

In order to throw the keeper out of engagement with the door and its supporting arm, the crank-wheel is provided with a shoulder *5* upon its periphery, which engages the shoulder *6* upon the keeper when the crank-wheel is rotated to the right from the position shown in Fig. 2. The initial movement of the crank-wheel in the direction to permit the door to open causes the shoulder *5* to throw the keeper out of engagement with the supporting arm and release the door. The continued rotation of the crank-wheel in the same direction permits the door to be lowered to any desired position and it may be held at any desired incline by preventing the further rotation of the crank-wheel when such inclined position is reached. To limit the movement of the crank-wheel in a direction to close the door, it is provided with a shoulder *7*, which engages a pin *8* upon the transverse beam.

In order to provide suitable means for operating the main shafts and thereby the doors through the medium of the mechanisms above described, each of such main operating shafts is provided at at least one end thereof with a pinion *18*, in which meshes with a pinion *9*, the latter being operatively connected with a hand-wheel *10*, by means

of a shaft *11*, having a beveled gear *12* at its lower end, and a beveled gear *13* connected with the pinion *9* and meshing with the bevel gear of such shaft. By this arrangement the operating shaft is so geared down that it may be operated manually by means of the hand-wheel. The rotation of the hand-wheel in one direction causes a corresponding rotation of the main shaft and crank-wheels on one side of the car, so as to permit the doors on that side to open, and its rotation in the opposite direction will cause the doors to be raised to closed position and permit the keepers to be thrown into position to support the weight of such doors and any load which may be placed thereon.

In order to strengthen the transverse beams and afford a rigid connection between such beams and the longitudinal sills, braces *14* are riveted firmly to such members as shown in Figs. 2 and 3.

I claim:

1. In a dump car of the class described, the combination of a car frame, a crank-wheel mounted in the framework of the car, a dumping door movable to closed position above the level of the top of the crank wheel, and means for connecting such crank-wheel with the dumping door, substantially as described.

2. In a dumping car, the combination of a frame having transverse beams and means for supporting the beams, of swinging dumping doors, crank mechanism mounted on the transverse beams below the level of the doors when the doors are in closed position, the crank mechanism having a fixed pivotal connection with the dumping doors, and means for operating the crank mechanism.

3. In a dump car of the class described, the combination of a car frame provided with longitudinal sills and transverse beams, crank mechanism mounted adjacent to such transverse beams, swinging dumping doors, means for connecting such crank mechanism with the dumping doors, a main operating shaft, and means for connecting such main operating shaft with the crank mechanism, substantially as described.

4. In a dump car of the class described, the combination of a car frame provided with longitudinal sills, hollow transverse beams mounted upon such sills, crank-wheels mounted in such hollow transverse beams, swinging dumping doors, means for connecting such crank-wheels with the dumping doors, a main operating shaft, means for connecting such main operating shaft with the crank-wheels, and means for operating the main shaft, substantially as described.

5. In a car of the class described, the combination of a supporting framework, dumping doors, mechanism mounted between the ends of the dumping doors entirely below the level of the upper surface of the doors

- when they are in closed position and provided with connecting door-supporting mechanism in engagement with such doors intermediate the outer lateral edges and longitudinal centers thereof, and means for operating such mechanism and thereby the dumping doors, substantially as described.
6. In a car of the class described, the combination of longitudinal sills, a plurality of transverse beams mounted upon and extending over the longitudinal sills from one side to the other of the car each having side portions provided with a space therebetween and an upper portion connecting such side portions, all forming a framework, and dumping doors movably mounted in the framework formed by such longitudinal sills and transverse beams, substantially as described.
7. In a car of the class described, the combination of longitudinal sill mechanism, transverse beams mounted upon and extending over such longitudinal sill mechanism from one side to the other of the car, dumping doors, and mechanism mounted upon such transverse beams and connected with the dumping doors for operating such doors, substantially as described.
8. In a car of the class described, the combination of a supporting framework provided with transverse beams having side portions provided with a space therebetween, means for supporting such transverse beams, dumping doors, and mechanism mounted in the space between the side portions of such transverse beams below the closed position of and connected with the dumping doors for operating them, substantially as described.
9. In a car of the class described, the combination of longitudinal sill mechanism, transverse beams, each having side portions provided with a space therebetween and an upper portion connecting such side portions, dumping doors, and mechanism mounted in the space between the side portions of such transverse beams below the closed position of and connected with the dumping doors for operating them, substantially as described.
10. In a car of the class described, the combination of longitudinal sill mechanism, a plurality of transverse beams mounted upon and extending over such longitudinal sill mechanism from one side to the other of the car each consisting of a pair of side members provided with a space therebetween, and an upper member connected to and connecting such side members, substantially as described.
11. In a dump car of the class described, the combination of a car frame provided with longitudinal sills, hollow transverse beams mounted upon such sills, crank-wheels mounted in such hollow transverse beams, swinging dumping doors, links pivotally mounted upon such crank-wheels and connected with such dumping doors, main operating shaft mech-
- anism, means for connecting such main operating shaft mechanism with the crank-wheels, and means for operating such main operating shaft mechanism, substantially as described.
12. In a dump car of the class described, the combination of a car frame, a dumping door, a keeper mounted upon the framework of the car movable into and out of operative engagement with the dumping door for supporting and releasing such door, mechanism connected with the door for operating it, and means connected with and operated by the door-operating mechanism for operating the keeper, substantially as described.
13. In a dump car of the class described, the combination of a car frame, a dumping door provided with a supporting arm, a keeper mounted upon the framework of the car movable into and out of engagement with such supporting arm for supporting and releasing the door, means for operating such dumping door, and means connected with and operated by the door-operating mechanism for operating the keeper, substantially as described.
14. In a dump car of the class described, the combination of a car frame, a plurality of dumping doors, keeper mechanism mounted upon the framework of the car movable automatically into operative engagement with such dumping doors for supporting them, mechanism connected with the dumping doors for operating them, and means connected with and operated by the door-operating mechanism for releasing such keeper mechanism, substantially as described.
15. In a dump car of the class described, the combination of a car frame, a dumping door provided with a supporting arm, a keeper pivotally mounted in the framework of the car adapted to engage such supporting arm, a crank-wheel mounted in the framework of the car, means for connecting such crank-wheel with the dumping door, means for operating such keeper to release the dumping door, and means for operating the crank-wheel, substantially as described.
16. In a dump car of the class described, the combination of a car frame, a dumping door provided with a supporting arm, a keeper pivotally mounted in the framework of the car adapted to engage such supporting arm, a crank-wheel mounted in the framework of the car provided with means for operating such keeper to release the dumping door, means for connecting such crank-wheel with the dumping door, and means for operating such crank-wheel and thereby the keeper and dumping door, substantially as described.
17. In a dump car of the class described, the combination of a car frame provided with hollow transverse beams, a crank-wheel mounted upon each of a plurality of such

transverse beams entirely below the level of the upper surface of the dumping doors when in their closed position, dumping doors mounted intermediate the transverse beams, means for connecting such dumping doors with the crank-wheels, a main operating shaft, sprocket wheels mounted on such main shaft inside the hollow transverse beams, and chain and sprocket mechanism for connecting such main operating shaft with the crank-wheels, substantially as described.

18. In a car of the class described, the combination of a dumping door, a shaft upon which such dumping door is pivotally mounted, and mechanism operated by such shaft and connected with the dumping door for operating such door, substantially as described.

19. In a car of the class described, the combination of dumping doors, a shaft upon which such doors are pivotally mounted, mechanism connected with such shaft and dumping doors for operating the doors, and means for operating such shaft and thereby the dumping doors, substantially as described.

20. In a dump car of the class described, the combination of a car frame provided with transverse beams, crank mechanism mounted upon each of a plurality of such transverse beams, sprocket-wheel mechanism connected with such crank mechanism, a main operating shaft provided with sprocket-wheels mounted thereon, chains mounted upon and connecting such sprocket-wheels and thereby the main operating shaft with the crank mechanism, dumping doors pivotally mounted upon the main shaft, and means for connecting such dumping doors with the crank mechanism, substantially as described.

21. In a dump car of the class described, the combination of a car frame, crank mechanism mounted upon such frame, a main operating shaft, chain and sprocket mechanism connecting such main operating shaft with the crank mechanism, dumping doors pivotally mounted and provided with depending brackets, and a link pivotally connected with each of such depending brackets and with such crank mechanism, substantially as described.

22. In a dump car of the class described, the combination of a car frame, crank-wheels rotatably mounted in such frame, a main operating shaft provided with sprocket wheels mounted thereon, chain mechanism

mounted upon and connecting such sprocket-wheels and thereby the main operating shaft with the crank-wheels, dumping doors pivotally mounted upon the main shaft and provided with depending brackets, links pivotally mounted upon such crank-wheels and pivotally connected to such depending brackets, depending supporting studs upon such doors, and a keeper mounted in the framework of the car movable into and out of engagement with such depending support studs, substantially as described.

23. In a dump car of the class described, the combination of a car frame provided with transverse beams, a crank-wheel mounted upon each of a plurality of such transverse beams, a main operating shaft with connecting such main operating shaft with the crank-wheels, a plurality of dumping doors each provided with a depending supporting bracket, and links pivotally mounted upon such crank-wheels and pivotally connected with each of such depending supporting brackets, substantially as described.

24. In a dump car of the class described, the combination of a car frame, a grooved crank-wheel mounted thereon and provided with sprocket teeth inside the grooved portion thereof, a dumping door, and means for connecting such grooved crank-wheel with the dumping door, substantially as described.

25. In a dump car of the class described, the combination of a car frame, swinging dumping doors, mechanism mounted in the car frame intermediate the ends of the dumping doors entirely below the upper level of the upper surface of the doors when they are in closed position and connected with the doors between their outer lateral edges and longitudinal centers for operating the doors, and means for operating such mechanism and thereby the doors, substantially as described.

26. A car having a series of doors in its floor arranged to swing in parallel planes, a series of separate stub-shafts having connections arranged to actuate each door, an operating shaft, and independent connections from each stub-shaft to the operating shaft, substantially as described.

SPENCER OTIS.
